VARIABLE VALVE TIMING CAMSHAFT

CROSS-REFERENCE TO RELATED
APPLICATION

The present application claims priority to Korean Patent Application No. 10-2013-0157594 filed Dec. 17, 2013, the entire contents of which is incorporated herein for all purposes by this reference.

BACKGROUND OF THE INVENTION

Field of the Invention

The present invention relates to a variable valve timing camshaft. More particularly, the present invention relates to a variable valve timing camshaft which is adapted to vary open/close timing of a valve.

Description of Related Art

Generally, an intake valve which is selectively opened or closed so as to supply fuel for combustion and an exhaust valve which is selectively opened or closed so as to exhaust exhaust gas formed by the combusted fuel are provided in a combustion chamber of an engine.

The determining of open/close timing of the valve (intake valve or exhaust valve) may depend on a shape of a cam, rotation speed of a camshaft, and so on.

In detail, the cam rotates together with the camshaft to drive the valve, and the camshaft rotates by receiving torque from an engine. In addition, the time from when opening of the valve is started to when closing of the valve is ended and the lift of the valve are determined according to the shape of the cam, and the time from when opening of the valve is started to when closing of the valve is ended and the repetition cycle of opening/closing the valve are determined according to the rotation speed of the camshaft.

The rotation speed of the camshaft is generally proportional to the rotation speed of the engine. In addition, the optimally required open/close timing of the valve is varied according to the rotation speed of the engine. Therefore, it is required that the open/close timing of the valve is suitably varied according to the rotation speed of engine. Particularly, output and fuel consumption of the engine can be improved and simultaneously exhaust gas can be decreased if the open/close timing of the intake valve is suitably varied according to driving conditions including the rotation speed of the engine.

Meanwhile, the open/close interval between valves which are respectively disposed at combustion chambers which are provided in the engine may be determined by a phase difference along a circumferential direction between cams which open/close each valve.

An apparatus for controlling the open/close timing of the valve is one such as a continuous variable valve timing (CVVT) apparatus. In addition, the CVVT apparatus is operated to control the rotation speed of the camshaft and vary a phase difference along a circumferential direction between the cams.

However, reactivity or durability may be deteriorated if a connection structure with or composition of the CVVT apparatus for controlling the open/close timing of the valve and the camshaft is complex. In addition, interference with surrounding devices may occur.

The information disclosed in this Background of the Invention section is only for enhancement of understanding of the general background of the invention and should not be

2

taken as an acknowledgement or any form of suggestion that this information forms the prior art already known to a person skilled in the art.

5 BRIEF SUMMARY

Various aspects of the present invention are directed to providing a variable valve timing camshaft having advantages of having a simple composition and connection structure with a continuous variable valve timing apparatus, and simultaneously improving operating performance.

In addition, various aspects of the present invention are directed to providing a variable valve timing camshaft having further advantages of improving the connection structure with a CVVT apparatus and durability thereof.

According to various aspects of the present invention, a variable valve timing camshaft which may be connected to a continuous variable valve timing apparatus having a rotor and a stator which are adapted to relatively rotate with each other and may be operated to vary open/close timing of valve may include a non-control camshaft being coupled to the continuous variable valve timing apparatus, having a first drive gear rotating together with the rotor and a second drive gear rotating together with the stator, and rotating according to rotation of an engine without varying a phase along a circumferential direction, a control camshaft having an outer shaft rotating according to one of the first drive gear or the second drive gear, an inner shaft rotatably inserted into the outer shaft and rotating according to the other of the first drive gear or the second drive gear, an outer cam fixed to the outer shaft, and an inner cam fixed to the inner shaft, and adapted such that a phase along a circumferential direction is varied between the outer shaft and the inner shaft according to relative rotation of the rotor and the stator, and a limiting device limiting end play of the inner shaft.

The limiting device may be coupled with the inner cam, and the limiting device may include a limiting pin penetrating the outer shaft along a radial direction so as to be coupled with the inner shaft, and a limiting pin hole formed at the outer shaft such that the limiting pin penetrates it, in which an axial direction width of the limiting pin hole may be formed to be close in size to a diameter of the limit pin.

When at least two inner cams are disposed, the limit pin may be disposed at one of the at least two inner cams, and one limiting pin hole may be formed such that the limit pin is coupled thereto.

The limiting device may include a locking pin adapted to penetrate the outer shaft along a radial direction and to be inserted into the inner shaft, a locking groove formed along an external circumference of the inner shaft such that the locking pin is inserted thereto, and a locking pin hole formed at the outer shaft such that the locking pin penetrates the outer shaft.

The locking pin may be fixed to the locking pin hole.

A diameter of the locking pin hole may be formed to be smaller than a diameter of the locking pin, and the locking pin may be forcibly inserted into the locking pin hole.

An axial direction width of the locking groove may be formed to be close in size to a diameter of the locking pin.

It is understood that the term "vehicle" or "vehicular" or other similar terms as used herein is inclusive of motor vehicles in general such as passenger automobiles including sports utility vehicles (SUV), buses, trucks, various commercial vehicles, watercraft including a variety of boats and ships, aircraft, and the like, and includes hybrid vehicles, electric vehicles, plug-in hybrid electric vehicles, hydrogen-powered vehicles and other alternative fuel vehicles (e.g.,

fuel derived from resources other than petroleum). As referred to herein, a hybrid vehicle is a vehicle that has two or more sources of power, for example, both gasoline-powered and electric-powered vehicles.

The methods and apparatuses of the present invention have other features and advantages which will be apparent from or are set forth in more detail in the accompanying drawings, which are incorporated herein, and the following Detailed Description, which together serve to explain certain principles of the present invention.

BRIEF DESCRIPTION OF THE DRAWINGS

FIG. 1 is a schematic diagram of a basic continuous variable valve timing apparatus which is connected with an exemplary variable valve timing camshaft according to the present invention.

FIG. 2A, FIG. 2B, and FIG. 2C are drawings which show a connection structure of the exemplary variable valve timing camshaft and the continuous variable valve timing apparatus according to the present invention.

FIG. 3A, FIG. 3B, and FIG. 3C are drawings which show a connection structure of an exemplary variable valve timing camshaft and a continuous variable valve timing apparatus according to the present invention.

FIG. 4 is a drawing which shows a coupling structure of an inner cam of an exemplary variable valve timing camshaft according to the present invention.

FIG. 5 is a drawing which shows a coupling structure of an inner cam of an exemplary variable valve timing camshaft according to the present invention.

It should be understood that the appended drawings are not necessarily to scale, presenting a somewhat simplified representation of various features illustrative of the basic principles of the invention. The specific design features of the present invention as disclosed herein, including, for example, specific dimensions, orientations, locations, and shapes will be determined in part by the particular intended application and use environment.

DETAILED DESCRIPTION

Reference will now be made in detail to various embodiments of the present invention(s), examples of which are illustrated in the accompanying drawings and described below. While the invention(s) will be described in conjunction with exemplary embodiments, it will be understood that the present description is not intended to limit the invention(s) to those exemplary embodiments. On the contrary, the invention(s) is/are intended to cover not only the exemplary embodiments, but also various alternatives, modifications, equivalents and other embodiments, which may be included within the spirit and scope of the invention as defined by the appended claims.

FIG. 1 is a schematic diagram of a basic continuous variable valve timing apparatus which is connected with a variable valve timing camshaft according to various embodiments of the present invention.

As shown in FIG. 1, the continuous variable valve timing (CVVT) apparatus 10 basically includes a rotor 15, a stator 16, and a vane 14. In addition, a gear or a chain sprocket 11 may be mounted at the CVVT apparatus 10.

The gear or the chain sprocket 11 is connected with a gear or a sprocket by a member such as a belt or a chain rotating together with a crankshaft so as to synchronize rotation of an

engine and rotation of a variable valve timing camshaft 1. Hereinafter, the gear or the chain sprocket 11 will be called a chain sprocket 11.

One of the rotor 15 and the stator 16 composing the CVVT apparatus 10 is fixed to the chain sprocket 11 so as to be driven by rotation of the engine, and the other of the rotor 15 and the stator 16 is driven by a hydraulic pressure type of control apparatus or an electrical control apparatus. Therefore, the rotor 15 and the stator 16 relatively rotate with each other according to the operation of the CVVT apparatus 10.

The one of the rotor 15 and the stator 16 is coupled with an outer shaft 20 of the variable valve timing camshaft 1, and the other of the rotor 15 and the stator 16 is coupled with an inner shaft 25 of the variable valve timing camshaft 1 (Referring to FIG. 2C and FIG. 3C). That is, the CVVT apparatus 10 is connected with the variable valve timing camshaft 1. Therefore, a relative phase along a circumferential direction of the outer shaft 20 and the inner shaft 25 may be varied according to the operation of the CVVT apparatus 10.

FIG. 2A, FIG. 2B, and FIG. 2C are drawings which show a connection structure of a variable valve timing camshaft and a continuous variable valve timing apparatus according to various embodiments of the present invention.

As shown in FIG. 2A, FIG. 2B, and FIG. 2C, the variable valve timing camshaft 1 includes a non-control camshaft 2 and a control camshaft 3, and the CVVT apparatus 10 includes the chain sprocket 11 in a connection structure with the variable valve timing camshaft 1 according to various embodiments of the present invention and the CVVT apparatus 10.

The non-control camshaft 2 is coupled with the chain sprocket 11 rotating according to rotation of an engine so as to rotate together therewith, and is not operated to vary open/close timing of a valve. The CVVT apparatus 10 is coupled with the non-control camshaft 2.

The control camshaft 3 is a camshaft-in-camshaft. The camshaft-in-camshaft includes the outer shaft 20 and the inner shaft 25. In addition, the outer shaft 20 is formed with a hollow cylindrical shape, and the inner shaft 25 is inserted into the hollow of the outer shaft 20 so as to be concentrically disposed with the outer shaft 20. Further, at least one of the outer shaft 20 and the inner shaft 25 may be rotated by a predetermined rotation angle with respect to the other such that a relative phase along a circumferential direction of the outer shaft 20 and the inner shaft 25 can be varied. The basic composition of the camshaft-in-camshaft is well-known to a person of ordinary skill in the art, so a detailed description thereof will be omitted.

The control camshaft 3 includes the outer shaft 20, an outer cam 48 fixed to the outer shaft 20, the inner shaft 25 rotatably inserted into the outer shaft 20, and an inner cam 40 fixed to the inner shaft 25 and rotatably disposed on the outer shaft 20.

The control camshaft 3 is operated so as to vary at least one open/close timing of a valve which is opened or closed by the outer cam 48 and a valve which is opened or closed by the outer cam 48 according to a variation in a relative phase along a circumferential direction of the outer cam 48 and the inner cam 40.

The CVVT apparatus 10 includes the rotor 15 and the stator 16.

The one of the rotor 15 and the stator 16 can relatively rotate with respect to the other. In addition, the one of the rotor 15 and the stator 16 is gear-connected with the outer shaft 20, and the outer shaft 20 is rotated by rotation of the

one of the rotor **15** and the stator **16**. Further, the other of the rotor **15** and the stator **16** is gear-connected with the inner shaft **25**, and the inner shaft **25** is rotated by rotation of the other of the rotor **15** and the stator **16**.

The rotor **15** is adapted such that a first drive gear **12** is mounted thereto, and the stator **16** is adapted such that a second drive gear **13** is mounted thereto. The rotor **15** and the first drive gear **12** are coupled by a fixing pin **30** so as to rotate together. That is, the rotor **15** and the first drive gear **12** have equal phases along a circumferential direction.

The first drive gear **12** and the second drive gear **13** are respectively gear-connected with a first driven gear **21** which is mounted at one side of the inner shaft **25** and a second driven gear **22** which is mounted at one side of the outer shaft **20**. Therefore, the rotor **15** is connected with the inner shaft **25** by the gear-connection, and the stator **16** is connected with the outer shaft **20** by the gear-connection.

The chain sprocket **11** is coupled to and fixed to the rotor **15** and the non-control camshaft **2** by a CVVT apparatus bolt **31**. In addition, the chain sprocket **11** is coupled to and fixed to the first drive gear **12** by a chain sprocket bolt **18**. Therefore, the rotor **15**, the non-control camshaft **2**, and the first drive gear **12** are driven according to rotation of the engine.

Hereinafter, operation in which open/close timing of a valve, which is operated by the control camshaft **3**, is varied in a connection structure with the variable valve timing camshaft **1** and the CVVT apparatus **10** according to various embodiments of the present invention will be described.

The stator **16** relatively rotates with the rotor **15** by hydraulic pressure flowing in through an oil hole **32** which is formed at the CVVT apparatus bolt **31**. Therefore, a relative phase along a circumferential direction of the rotor **15** and the stator **16** is varied.

A rotation ratio between the inner shaft **25** and the engine is not changed according to the rotor **15** being connected with the inner shaft **25** by the gear-connection of the first drive gear **12** and the first driven gear **21**.

The phase of the outer shaft **20** is varied and open/close timing of a valve which is operated by the control camshaft **3** is varied according to the outer shaft **20** being connected with the stator **16** by the gear-connection of the second drive gear **13** and the second driven gear **22**, and the stator **16** is operated by a hydraulic pressure type of control apparatus.

FIG. 3A, FIG. 3B, and FIG. 3C are drawings which show a connection structure of a variable valve timing camshaft and a continuous variable valve timing apparatus according to various embodiments of the present invention.

As shown in FIG. 3A, FIG. 3B, and FIG. 3C, dispositions of the first drive gear **12** and the second drive gear **13** in a connection structure with a variable valve timing camshaft and a continuous variable valve timing apparatus according to various embodiments of the present invention are changed to compare with the connection structure with the variable valve timing camshaft and the continuous variable valve timing apparatus according to various embodiments of the present invention. Therein, the first drive gear **12** is connected with the second driven gear **22** rotating together with the outer shaft **20**, and the second drive gear **13** is connected with the first driven gear **21** rotating together with the inner shaft **25**.

Hereinafter, operation in which open/close timing of a valve, which is operated by the control camshaft **3**, is varied in a connection structure with the variable valve timing camshaft **1** and the CVVT apparatus **10** according to various embodiments of the present invention will be described.

The stator **16** relatively rotates with the rotor **15** by hydraulic pressure flowing in through the oil hole **32** which is formed at the CVVT apparatus bolt **31**. Therefore, a relative phase along a circumferential direction of the rotor **15** and the stator **16** is varied.

A rotation ratio between the outer shaft **20** and the engine is not changed according to the rotor **15** being connected with the outer shaft **20** by the gear-connection of the first drive gear **12** and the second driven gear **22**.

The phase of the inner shaft **25** is varied and open/close timing of a valve which is operated by the control camshaft **3** is varied according to the inner shaft **25** being connected with the stator **16** by the gear-connection of the second drive gear **13** and the first driven gear **21**, and the stator **16** is operated by a hydraulic pressure type of control apparatus.

In other words, the connection structure of the variable valve timing camshaft **1** and the CVVT apparatus **10** according to various embodiments of the present invention is a type

that varies the phase of the outer shaft **20**, and the connection structure of the variable valve timing camshaft **1** and the CVVT apparatus **10** according to various embodiments of the present invention is a type that varies the phase of the inner shaft **25**. Meanwhile, both the connection structure of

the variable valve timing camshaft **1** and the CVVT apparatus **10** according to various embodiments of the present invention and the connection structure of the variable valve timing camshaft **1** and the CVVT apparatus **10** according to various embodiments of the present invention are adapted such that the CVVT apparatus **10** is coupled with the non-control camshaft **2** of the variable valve timing camshaft **1**.

In the variable valve timing camshaft **1** in which the control camshaft **3** is not coupled with the CVVT apparatus

10, end play of the non-control camshaft **2** is limited by coupling a cam cap with the CVVT apparatus **10**, and the end play of the outer shaft **20** of the control camshaft **3** is limited by the cam cap. However, an additional composition is required for limiting the end play of the inner shaft **25** of the control camshaft **3**. Herein, the end play is play of a member such as a shaft that can move along an axial direction thereof.

FIG. 4 is a drawing which shows a coupling structure of an inner cam of a variable valve timing camshaft according to various embodiments of the present invention.

As shown in FIG. 4, the coupling structure of an inner cam of a variable valve timing camshaft according to various embodiments of the present invention includes a limiting pin **45** and a limiting pin hole **46**.

At least one inner cam **40**, which is provided to vary the phase thereof by varying the phase of the inner shaft **25**, is disposed at an exterior circumference of the outer shaft **20**. Herein, the outer cam **48** which varies the phase thereof by varying the phase of the outer shaft **20** is separately disposed with the inner cam **40** and is fixed to the outer shaft **20**. In addition, the inner cam **40** is coupled to the inner shaft **25** by a connecting pin **42** so as to rotate together with the inner shaft **25**.

The connecting pin **42** is coupled to the inner cam **40**, and penetrates the outer shaft **20** along a radial direction so as to couple to the inner shaft **25**. At this time, the outer shaft **20** has a connecting pin hole **43** such that the connecting pin **42** penetrates thereto.

The connecting pin hole **43** has a set length along a circumferential direction such that relative rotation of the outer shaft **20** and the inner shaft **25** is possible. Meanwhile, an axial direction width of the connecting pin hole **43** is

formed to be longer than a diameter of the connecting pin **42** for smoothly operating. Thus, the end play of the inner shaft **25** occurs.

If the at least one inner cam **40** is two or more, the limit pin **45** is a pin such as the connecting pin **42** for mounting one of the two or more inner cams **40**. In addition, the outer shaft **20** has the limiting pin hole **46** such that the limit pin **45** penetrates the outer shaft **20**.

An axial direction width of the limiting pin hole **46** is formed to be close to a diameter of the limit pin **45** for limiting the end play of the inner shaft **25**.

FIG. 5 is a drawing which shows a coupling structure of an inner cam of a variable valve timing camshaft according to various embodiments of the present invention.

As shown in FIG. 5, the coupling structure of an inner cam of a variable valve timing camshaft according to various embodiments of the present invention includes a locking pin **27**, a locking groove **28**, and a locking pin hole **29**.

The locking pin **27** penetrates the outer shaft **20** from an exterior circumference to the hollow along a radial direction, and is disposed to be inserted into the inner shaft **25**.

The locking groove **28** is formed at the inner shaft **25** such that the locking pin **27** is inserted thereto. In addition, the locking groove **28** is formed along an external circumference of the inner shaft **25**.

The locking pin hole **29** is formed at the outer shaft **20** such that the locking pin **27** penetrates the outer shaft **20**. In addition, the locking pin **27** is fixed to the locking pin hole **29**. For example, a diameter of the locking pin hole **29** may be formed to be smaller than a diameter of the locking pin **27**, and the locking pin **27** may be forcibly inserted into the locking pin hole **29**.

An axial direction width of the locking groove **28** is formed to be close to a diameter of the locking pin **27** for limiting the end play of the inner shaft **25**.

According to various embodiments of the present invention, accuracy of the valve timing control may be better, and reactivity and operational efficiency may be improved. In addition, vibration and noise may be minimized, and durability may be ensured.

For convenience in explanation and accurate definition in the appended claims, the terms "upper", "lower", "inner" and "outer" are used to describe features of the exemplary embodiments with reference to the positions of such features as displayed in the figures.

The foregoing descriptions of specific exemplary embodiments of the present invention have been presented for purposes of illustration and description. They are not intended to be exhaustive or to limit the invention to the

precise forms disclosed, and obviously many modifications and variations are possible in light of the above teachings. The exemplary embodiments were chosen and described in order to explain certain principles of the invention and their practical application, to thereby enable others skilled in the art to make and utilize various exemplary embodiments of the present invention, as well as various alternatives and modifications thereof. It is intended that the scope of the invention be defined by the Claims appended hereto and their equivalents.

What is claimed is:

1. A variable valve timing camshaft which is connected to a continuous variable valve timing apparatus having a rotor and a stator which are adapted to relatively rotate with each other and is operated to vary open/close timing of a valve, the variable valve timing camshaft comprising:

a non-control camshaft coupled to the continuous variable valve timing apparatus, having a first drive gear rotating together with the rotor and a second drive gear rotating together with the stator, the non-control camshaft rotating according to rotation of an engine; a control camshaft having an outer shaft rotating according to one of the first drive gear or the second drive gear, an inner shaft rotatably inserted into the outer shaft and rotating according to the other of the first drive gear or the second drive gear, an outer cam fixed to the outer shaft, and an inner cam fixed to the inner shaft, wherein a phase along a circumferential direction is varied between the outer shaft and the inner shaft according to relative rotation of the rotor and the stator; and

a limiting device limiting end play of the inner shaft, wherein the limiting device includes:

a locking pin penetrating the outer shaft along a radial direction and to be inserted into the inner shaft;

a locking groove formed along an external circumference of the inner shaft such that the locking pin is inserted thereto; and

a locking pin hole formed at the outer shaft such that the locking pin penetrates the outer shaft.

2. The variable valve timing camshaft of claim 1, wherein the locking pin is fixed to the locking pin hole.

3. The variable valve timing camshaft of claim 2, wherein a diameter of the locking pin hole is formed to be smaller than a diameter of the locking pin, and the locking pin is forcibly inserted into the locking pin hole.

4. The variable valve timing camshaft of claim 1, wherein an axial direction width of the locking groove is formed to be approximately in size to a diameter of the locking pin.
